UNITED STATES PATENT OFFICE.

CLATON E. BURKE AND GROVE R. BECKWITH, OF MINNEAPOLIS, MINNESOTA.
ASSIGNORS TO B. B. SPECIALTY CO., OF MINNEAPOLIS, MINNESOTA, A CORPORATION OF MINNESOTA.

MOP-HOLDER.

1,311,316.

Specification of Letters Patent. Patented July 29, 1919.

Application filed April 27, 1918. Serial No. 231,170.

To all whom it may concern:

Be it known that we, CLATON E. BURKE and GROVE R. BECKWITH, citizens of the United States, residing at Minneapolis, in 5 the county of Hennepin and State of Minnesota, have invented certain new and useful Improvements in Mop-Holders; and we do hereby declare the following to be a full, 10 clear, and exact description of the invention, such as will enable others skilled in the art to which it appertains to make and use the same.

This invention has for its object to provide an extremely simple and highly efficient mop head or mop holder; and, to such ends, generally stated, the invention consists of the novel devices and combinations of devices hereinafter described and defined in the claims.

20 The invention is illustrated in the accompanying drawings, wherein like characters indicate like parts throughout the several views.

Referring to the drawings:—

25 Figure 1 is a plan view showing the improved device;

Fig. 2 is a side elevation thereof; and

Fig. 3 is a section on the line 3—3 of Fig. 1.

30 The numeral 4 indicates an ordinary pole or handle, preferably of wood, provided at its end with a ferrule 5. Secured to the end of the pole or handle 4, is an approximately rectangular head frame 6 formed 35 from a piece of heavy wire bent to form prongs that are inserted into that end of the handle which is surrounded by the ferrule 5. The sides of the frame 6 are parallel, but, at the junction with the transverse portion 6^a of said frame, said wire is bent to form outwardly projected bulges 6^b. Rigidly secured to the parallel sides of the frame 6, adjacent to its converging or pronged ends, is a transverse bar 7 that not 40 only serves as a brace, but as an abutment for a pair of clamping toggles, made up of toggle members 8 and 9. The toggle members 8 are pivoted to the bar 7, while the toggle members 9 are normally free at both 45 ends and intermediately pivoted to the free ends of the toggle members 8 at 10. Stop pins 11, on the toggle members 8, engage the toggle members 9 to limit the buckling movements of the toggles in one direction 50 and, as shown, said toggle members 9 are

provided with small notches with which the pins 11 directly engage.

Mounted to slide on the parallel heads of the head frame 6, is a clamping bar 12 of channel form, preferably stamped from a 60 sheet of metal. The flanges of this clamping bar 12 lap with clearance on opposite sides of the transverse coöperating clamping bar or portion 6^a of the head frame 6. In its back, the clamping bar 12 is provided 65 with longitudinally spaced perforations 13 in which the pointed ends of the toggle members 9 are engageable.

When the toggles are buckled, as shown by dotted lines in Fig. 1, they may be swung 70 out of position and the clamping bar 12 may be retracted on the side of the frame 6, so as to allow insertion into position of the mop cloth 14. Then, when the clamping bar is slid back against the mop cloth, as shown 75 in Fig. 2, the pointed ends of the toggle members 9 will be inserted into the proper members of the insertion 13 and the toggles will then be first straightened to dead centers and then moved slightly beyond dead 80 centers, until stop pins 11 strike against toggle members 8. The toggles will then be locked in position slightly beyond dead centers. The upper ends of the toggle members 85 9 are bent outward, so as to afford suitable finger pieces. The several perforations 13 permit adjustments to adapt the clamping bar to mops of different thicknesses. Obviously, for thick cloths, the pointed ends 90 of the toggle members 9 will be inserted into perforations 13 that are nearer to the center of the clamping bar.

The mop holder described may be made at very small cost and is efficient for the purpose had in view. It will securely hold 95 a mop and provides for quick and easy adjustment to clamp or release the mop cloth.

What we claim is:—

1. A mop holder comprising a head frame, a clamping bar slidable on said frame and a 100 toggle pivotally anchored to said head and detachably engageable with said clamping bar.

2. A mop holder comprising a head frame, a clamping bar slidable on said head frame 105 and having longitudinal lever seats, and a pair of toggles pivotally anchored to said head frame and having free ends engageable with the seats in said clamping bar.

3. A mop holder comprising a handle, a 110

- head frame made from a piece of wire bent to form parallel sides and a transverse clamping bar and having prongs secured to said handle, an anchor bar rigidly secured 5 to the sides of said frame, a clamping bar 10 slideable on the sides of said head frame, and a pair of toggles pivoted to said anchor bar and having free ends detachably engageable with said clamping bar.
- 10 4. A mop holder comprising a handle, a head frame made from a piece of wire bent to form parallel sides and a transverse clamping bar and having prongs secured to said handle, an anchor bar rigidly secured 15 to the sides of said frame, a clamping bar slideable on the sides of said head frame, and

a pair of toggles pivoted to said anchor bar and having free ends detachably engageable with said clamping bar, the said toggles being limited in their buckling movements in one direction to positions slightly beyond dead centers, the said clamping bar being channel-shaped and having in its back longitudinal perforations with which the free ends of said toggles are engageable. 20

In testimony whereof we affix our signatures in presence of two witnesses:

CLATON E. BURKE.

GROVE R. BECKWITH.

Witnesses:

CLARA DEMAREST,
F. D. MERCHANT.
